UNITED STATES PATENT OFFICE

168,013

CENTRIFUGAL SEPARATOR

Conrad F. Åller, Stockholm, Sweden, assignor to
Aktiebolaget Separator, Stockholm, Sweden, a
corporation of Sweden

Application September 16, 1949, Serial No. 5,045

Term of patent 14 years

(Cl. D23—1)

To all whom it may concern:

Be it known that I, Conrad Ferdinand Åller, a subject of the King of Sweden, residing at Stockholm, Kingdom of Sweden, have invented a new, original, and ornamental Design for Centrifugal Separator, of which the following is a specification, reference being had to the accompanying drawing, forming a part hereof.

Fig. 1 is a front elevation of a centrifugal separator, showing my new design;

Fig. 2 is a side elevation thereof; and

Fig. 3 is a plan view.

The characteristic features of the design reside in the solid line portions.

I claim:

The ornamental design for a centrifugal separator, as shown and described.

CONRAD F. ÅLLER.
